AIRWAY ELBOW ATTACHMENT FOR HOSE EXTENSIONS

Filed June 6, 1928

UNITED STATES PATENT OFFICE

DANIEL BENSON REPLEGGE, OF BERKELEY, CALIFORNIA, ASSIGNOR, BY DIRECT AND MESNE ASSIGNMENTS, TO THE COMMERCE GUARDIAN TRUST & SAVINGS BANK, TRUSTEE, OF TOLEDO, OHIO

AIRWAY ELBOW ATTACHMENT FOR HOSE EXTENSIONS

Application filed June 6, 1928. Serial No. 283,278.

This invention relates to accessories and extensions in airway cleaning systems commonly known as vacuum cleaners and has to do with converting portable cleaners into stationary or semi-stationary form. The general purpose is to conveniently extend hose pipe connections from the suction handle of portable machines or from the suction handle extension of stationary machines, such as are shown, for example, in my Patent No. 1,533,271, dated August 14, 1925.

The more particular objects are to make convenient the closeting of portable devices, to render the closeted machine suitable for stationary service, to make a convenient hose hanger ready to receive the closeted cleaner into working relation with the hose, to fasten such hose hanger to partitions or walls of dwellings, or to the swinging doors of the closets therein, and other objects as may appear in the specifications and claims.

In my Patent No. 1,681,624, dated August 21, 1928, entitled "Air-way cleaning cabinet," I have disclosed a cabinet adapted to support a cleaner of the air-way type with its suction handle in upright position, whereby the same may be operatively connected to an extension hose or the like, and the present application, as to certain features of the invention, constitutes an improvement over the system disclosed in the aforesaid patent.

To these ends the invention consists of the construction, design, arrangement and combination of the parts and features herein specified and illustrated in the accompanying drawing, in which:

Fig. 1 shows a front elevation of the hose hanger partly in section and suggesting movements of an L thereof in dotted lines. Fig. 2 shows a section of one of the metal stampings, four of which similar stampings are used in constructing the double L shown in Fig. 1.

Fig. 3 shows an elevation taken at right angles to that of Fig. 1, but with the L members in other adjustments than those shown.

Fig. 4 shows an airway cleaner and an extension hose thereof when attached to a partition or the door of a closet in connection with the hose hanger.

Fig. 5 is a front view of a suitable support on which to set or rest the rollers of the closeted cleaner when used in connection with my hanger.

Fig. 6 is a fragmentary view showing a modification in which the tool is attached directly to the L.

Similar characters of reference denote like and corresponding parts throughout the several views.

In the drawing, 1 denotes a part of an upright wall, partition or door, to which is secured the attachment bracket 2, with a base 3, having screw holes 4, 4. To a lower portion of the door 1, a rest 5 may be attached by screws passing through the bores 6, 6, thereof, which latter rest is designed to carry the entire weight of the cleaner with which my device is used.

The device properly comprises a pair of elbows or sections 7 and 7', which may preferably be constructed from similar stampings, being each a pair of L-shaped shells 8, 8, semi-circular in cross section and having flanges 8' and 8" which may be spot-welded together in forming them. They are completed by assembling rings 9 and 10, rigidly secured to abutting ends of the L's, and the interconnecting flanges of these rings slide freely so as to permit the L's to have relative rotary motion. The bracket 2 is designed to grasp the outer flange of the ring 9, by a springing or yieldable hold, while allowing free rotation, yet the flange of the ring 10 is designed to slide more freely within the curved outer flange of the ring 9.

The outer end of the L 7 has a flaring ring member 11 adapted to rotatably receive the end of a suction pipe 13 of a cleaning system; and the outer end of the L 7' has a nipple ring member 12 adapted to have slipped over it, the end 14 of the suction hose 15 of a cleaning system. These rings 11 and 12, assist in assembling the halves of the L's and are shown in section in Fig. 1.

In addition to the yieldable hold of the bracket 2 upon the ring 9, in its grasping end 2', the bracket is flexible throughout its length so that when the pipe 13 of the supported cleaner 16, is to be connected to the member 100

11, the supported L's with the connected hose 15 may be slightly bent or sprung upwards so as to slip over and operatively connect with the end of the pipe 13.

5 The utility of the device consists in connecting the end of the suction pipe with a suction hose and furnishing a swivel pipe connection and extension, for freely reaching in various directions. This utility is enhanced by the 10 means for suspending the swivel pipe connection from an attachment to an upright partition, wall or door; for it is apparent that the cleaner 16 may be removed by separating it from the ring 11 for floor sweeping purposes, 15 or the handle end may remain connected to the ring, and the elbow device may be disengaged from the bracket end 2' so that the end of the pipe 13 may carry with it the L member with its swivelling pipe joint and 20 the hose pipe extension connecting therewith, to be used for cleaning purposes other than floor sweeping. It is to be understood that when the cleaner is connected as shown, for many convenient purposes it may be put 25 into operation by turning the valve 20 of the cleaner to direct suction through its pipe handle portion 13, in the manner disclosed in my Patent No. 1,345,550, dated July 6, 1920, so as to use any ordinary application tool as 30 17 on the hose 15, when the L joint member is not removed from the bracket 2. It is apparent, also, that the tool 17 may be attached directly to the elbow end 7' as shown in Fig. 6 as well as intermediately by the hose-pipe 35 15; and in any case, the attached portion yieldingly rotates in or on the end of the elbow to which it is attached so as to accommodate itself to the demands of the operator.

40 It will be understood that one of the important results accomplished by my invention is the ready conversion of a normally portable suction cleaner, which includes a source of suction and a suction pipe or handle in operative communication therewith, into a semi-stationary machine to which extensions may 45 be applied, and which may be conveniently used for the cleaning of walls, ceilings, draperies and the like. The means by which this conversion is accomplished is the flexible 50 and resilient bracket arm 2, which may be suitably secured to a relatively stationary member, such as a wall, door or the like. The flexible bracket arm carries with it a hollow connector or coupling, one end of which is 55 designed to receive the open end of the suction handle. According to the embodiment of the invention as herein disclosed, the hollow connector is shown as composed of two rotatably connected elbow pipe sections 7, 7', but it will 60 be apparent that so far as the broad aspects of the invention are concerned, the number of sections of which the hollow connector is composed may be varied without departing from the spirit of the invention, and the term 65 "hollow connector" as used in the accompany-

ing claims is to be given a broad interpretation.

Having thus described the device and its operation, I desire not to be restricted to the specific construction shown and described, but 70 claim more broadly:

1. In a cleaning system, a pair of L pipe members, means for operatively and rotatively connecting two of their ends together, suction conduits connected to their other ends, 75 a bracket and means for attaching the connected L members rotatively to said bracket.

2. In a suction cleaning system, a pair of rotatably connected pipe sections, flanged at their abutting portions and having a ring 80 connecting said flanges, a pair of cleaner pipes operatively connected to said pipe sections, and a bracket for supporting said pipe sections having a portion rotatably engaging said ring member.

3. In a device of the character described, in combination a pair of abutting pipe sections having flanges at their abutting portions, a ring member rotatably connecting said flanges, and a flexible bracket for supporting said pipe sections having a portion engaging said ring member with a springing and yieldable hold, allowing rotation of the ring relative to the bracket, at the same time that the pipe sections are movable relative to each other and with reference to the ring member.

4. In combination with a suction cleaner having a suction handle, an upright having a resilient bracket arm, a hollow connector carried by said bracket arm and connected at one end to said suction handle, and an extension pipe operatively connected at the other end of said hollow connector.

5. In combination with a suction cleaner having a suction handle, means for supporting said handle in upright position and serving as a coupling for additional cleaning pipes, said means including a hollow connector having one end fitting over said suction handle and the other end free to receive an extension pipe, and a resilient bracket arm supporting said hollow connector, the resilience of said bracket arm serving to hold said pipe section in air-tight connection with said suction handle.

6. In a device of the character described, in combination with a suction cleaner having a suction handle, a resilient holding bracket, said bracket carrying a hollow connector having one end fitting over said suction handle to hold it in upright position, and having its other end free to receive suction pipe extensions.

7. In combination, a suction cleaner having a suction handle, and an extension pipe, a hollow connector operatively connecting the suction handle and said extension, and a supporting bracket removably and rotatably connected to said hollow connector.

8. In combination, a suction cleaner having a suction handle, an extension pipe, a hollow connector for operatively connecting said extension to said suction handle, and a flexible bracket removably and rotatably connected to said hollow connector. 5

9. A vacuum cleaning system comprising a source of suction, a tubular handle operatively connected to the source of suction, an 10 elbow having one end mounted on the end of said handle and the other rotatably connected with one end of a second elbow, said second elbow carrying at its other end, a suction nozzle rotatably mounted therein, the ends 15 of each of said elbows being approximately at right angles to each other, and a bracket for rotatably supporting said elbows. 15

10. In combination with a suction cleaner having a source of suction, an open-ended 20 suction handle operatively connected to the source of suction, and means, including a yielding bracket carrying a hollow coupling detachably connectible to the open end of the handle, for supporting the cleaner with 25 the suction handle in substantially upright position. 25

11. In combination with a suction cleaner having a source of suction, an open-ended 30 suction handle operatively connected to the source of suction, a floor tool connected with one end of the suction handle, and means for supporting the cleaner with the tool raised from the floor and the suction handle in substantially upright position, said means including 35 a yielding bracket carrying a hollow coupling detachably connectible at one end to the upper open end of the handle. 35

12. In combination with a suction cleaner, which cleaner includes a body and a suction 40 handle, a standard having means for supporting the body of the cleaner with its suction handle extending upwardly, a resilient bracket member carried by said standard extending toward the handle and having its free end 45 substantially on a level with but normally slightly below the upper end of the handle, a hollow connector carried by said resilient bracket fitting over said handle and forced 50 against the same by the resiliency of said bracket member. 55

13. A vacuum cleaner having an open-ended hollow handle, in combination with a support for said cleaner having resilient 55 means for pressing an extension tube and the open end of said handle against each other. 60

14. The combination with a suction cleaner having hinged roller supporting means at the lower portion thereof, and a suction handle 60 connected to a source of suction, of a standard having a lower bracket arm to receive said roller supporting means, and an upper bracket arm spaced from the lower arm and provided with means engaging said handle and 65 cooperating with the lower means to support 65

the cleaner with its suction handle in upright position. 70

15. The combination with a suction cleaner having hinged roller supporting means at the lower portion thereof, and a suction handle 70 connected to a source of suction, of a standard having a lower bracket arm to receive said roller supporting means, an upper bracket arm spaced from the lower arm and provided with means engaging said handle and 75 cooperating with the lower means to support the cleaner with its suction handle in upright position, and means for attaching a hose pipe to the upper end of said suction handle when the same is in the supported position. 80

16. A standard, for use with a suction cleaner, which cleaner includes a body, and an open-ended suction handle, said standard having means for supporting the body of the cleaner with its suction handle extending upwardly, a yielding bracket member carried by said standard, a hose pipe extension, and a pipe section carried by said yielding bracket and adapted for connection to said hose pipe extension, said pipe section being held against 90 the open end of said handle by said yielding bracket member. 85

17. In combination with a suction cleaner, which cleaner includes a body and a suction handle, a standard having means for supporting the body of the cleaner with its suction handle extending upwardly, a yielding bracket member carried by said standard, a hollow L member carried by said yielding bracket and held against said handle by said yielding 100 bracket member. 95

18. A standard for supporting a normally portable suction cleaner having an open-ended suction handle rigidly secured thereto, said standard comprising an upright portion having means for supporting the weight of the cleaner, a yielding bracket arm carried by said upright, and a hollow connector carried by said bracket arm and adapted to detachably engage the open end of said suction handle. 110

19. A standard designed for supporting a normally portable suction cleaner having an open-ended suction handle rigidly secured thereto with its suction handle in substantially upright position, said standard comprising an 115 upright portion, a bracket arm at the lower portion thereof for supporting the body of the cleaner, a yielding bracket arm spaced from the first-mentioned bracket arm, and a hollow coupling carried by the flexible bracket arm 120 for detachably engaging the upper open end of the suction handle. 120

20. In combination with a suction cleaner having a source of suction, an open-ended suction handle operatively connected to the 125 source of suction, a floor tool connected with one end of the suction handle, a hinged roller support mounted at the lower portion of the cleaner, and means cooperating with said roller support for supporting said cleaner 130

with the floor tool downward and the suction handle in substantially upright position, said means including a standard comprising an upright portion, a trough-like bracket arm at the lower portion of said upright holding said hinged roller support, a flexible bracket arm at the upper portion of said upright, and a hollow coupling carried by said bracket arm and operatively engaging the open end of said suction handle.

21. An extension device for a suction cleaner having a hollow handle extending in a generally upward direction and open at its upper end, comprising a yielding bracket secured to an upright member at substantially the height of the upper open end of the cleaner handle, and an extension hose pipe having a hollow tip carried by said bracket, said tip when coupled with the hollow handle being carried so that it extends in a generally downward direction at about the angle of the upper portion of the cleaner handle.

22. An extension device for suction cleaners of a type having a hollow handle, comprising a yielding bracket carrying an open yielding clasp, and a hose extension pipe for said cleaner having a hollow tip detachably supported by said clasp, said clasp and hose being in engagement with each other when the extension device is in operative relationship with the cleaner.

23. In combination with a suction cleaner having a source of suction, and an open-ended suction handle rigidly secured to the cleaner and communicating with said source of suction; means for supporting the cleaner with the suction handle in substantially upright position, a bracket arm having a yielding clasp portion, and an extension hose pipe having a hollow tip carried by said clasp and detachably secured to the free upper end of the suction handle.

24. In a device of the character described, a yielding member and a hollow connector carried thereby, having its ends extending on opposite sides of the member, and adapted respectively for connection to the suction handle and hose extension members of an air-way cleaning system, said member and hollow connector being in engagement with each other when the ends of the hollow connector are in operative relation to the suction handle and hose extension members of the cleaning system.

25. In combination with a suction cleaner having a suction handle, a resilient supporting member, a hollow connector member carried by said resilient member, and yieldingly engaging the top of the suction handle, a second connector member operatively and rotatively connected to the first-mentioned connector member, and an extension pipe operatively connected to said second connector.

26. In combination with a suction cleaner, including a floor tool and suction handle, sup-

porting means for said cleaner, including a support for the floor tool, a resilient member located above the floor tool support, a hollow connector carried by the resilient member detachably engaging the top of the suction handle with a downward pressure at one end, and an extension pipe detachably connected to the other end of the connector.

In testimony whereof I affix my signature.
